UNITED STATES PATENT OFFICE

132,779

DESIGN FOR A RUG FASTENER

Ernest Berton Harris, Amarillo, Tex.

Application November 24, 1941, Serial No. 104,286

Term of patent 14 years

To all whom it may concern:

Be it known that I, Ernest Berton Harris, a citizen of the United States, residing at Amarillo, in the county of Potter in the State of Texas, have invented a new, original, and ornamental Design for a Rug Fastener, of which the following is a specification, reference being had to the accompanying drawing, forming part thereof.

I claim:

The ornamental design for a rug fastener, as shown.

ERNEST BERTON HARRIS.
